UNITED STATES PATENT OFFICE.

ROBERT M. SUTPHEN, OF NEWARK, NEW JERSEY, ASSIGNOR TO JOHN FRANCIS
BOORAEM, OF GREENWICH, CONNECTICUT.

ART OF MURAL DECORATION.

No Drawing.

Application filed November 2, 1926. Serial No. 145,918.

This invention relates to the art of mural decoration, and has for its primary object to provide a novel method for producing upon plaster walls a desired picture or scene and by means of which the proper blending of various different color mediums to obtain desired light and shade effects may be secured. My improved method also enables the representation of mist, fog, smoke and the like to be very realistically produced. Essentially, the method of mural decoration as it has been applied by me consists in superimposing upon the surface of the plaster wall a plurality of color mediums such as water color paint, oil and metallic paint, pastel, crayon, india ink, lead and various other color mediums which may be necessary to produce the desired effect in the completed picture. There is thus produced a laminated surface on the plaster wall, and I then by means of a suitable abrading tool, erase different parts of the superimposed color laminations on different portions of the wall to bring out and render visible the desired colors and thus obtain color effects which would not be possible by the application of the color mediums by means of a brush.

Heretofore, in the art of mural decoration, it has been impossible to combine such color mediums as above referred to for the purpose of producing a composite harmonious picture upon the surface of a plaster wall, owing to the fact that such color mediums will not blend with each other and also by reason of the peculiar action of the plaster on several of these materials. I have found however, that it is possible to produce such mural decorations by superimposing the several color mediums and interposing between the adjacent color mediums a third medium which acts as a spacer and a binder between the superimposed mediums. I have found it advisable to first apply to the surface of the plaster wall a coat of oil paint. After this coat has thoroughly dried, a coating of crayon is applied thereon and thoroughly rubbed in. Over this coat of crayon I then apply a coat of water color paint. After this latter coat has dried, a second coat of crayon is applied and then a coat of water color paint of a different color from that previously applied is superimposed upon this second crayon coat. In the same manner, any desired number of lami-

nations of different color mediums may be superimposed upon the wall surface, each of said mediums being of a different color from that upon which it is applied.

In cases where it is desired to use india ink upon the plaster surface, I find it advisable to first apply a coating upon the surface of the plaster, and for this purpose I preferably use a flat wash solution which I find to be quite closely related to the chemical peculiarities of the ink and to possess the virtue of binding and holding the ink upon the plaster without chemically modifying the ink or changing the color thereof.

After the superimposed color laminations have been applied to the wall surface, by means of a suitable scraping or abrading tool, I work back through the outermost lamination to the surface of the plaster wall removing various parts of the successive laminations to render the different colors visible at various areas of the wall in accordance with a preconceived design or scene which it is desired to produce. In this manner, I have been enabled to realistically depict upon a plaster wall such scenes as snow storms, sunsets, mists, fogs and various other scenes which would not otherwise be obtainable. Thus, upon reaching the original plaster base, a fine dust is created by the abrading action which will spread over the surrounding area in such a manner as to produce a fine hazy effect. In order to secure this dust in place, I use a transparent fixative solution which is applied at such places. I have also found it possible to so apply these various mediums in such quantities as to get a relief effect. Thus a coat of oil or water color may first be applied and then a relatively thick coat of a transparent gelatinous material superimposed thereon and permitted to harden. Over this material, a coating of Japanese water color is applied. I can thus produce the effect of two water colors actually spaced apart but without mixing. It is also possible to use pen and ink on the plaster surface, if this surface is first treated to provide a hard non-absorbent foundation for the ink. For this purpose oil or water color may be used. However, I have found that the plaster itself if the surface is sufficiently glazed and smooth, may be worked upon with pen and ink.

By the above method I am enabled to

produce a complete composite picture and to add various coloring media at different points without the necessity of blending of such added color media with the surface color, by merely cutting back through the superimposed laminations to a medium having the desired color or to the wall itself and then applying such additional coloring media. Thus, by cutting back to the bare plaster wall, said wall may then be colored to represent the sky, and by omitting the color at different area, the stars or the moon may be placed in the sky.

After the entire preconceived artistic design has thus been developed upon the wall surface a suitable transparent fixative material is applied thereover so as to preserve and protect the coloring media at the various exposed parts thereof.

Various colored dusts may be obtained by the application of pastel, crayon or water color and oils to the bare plaster and then abrading the same after thoroughly working in the color medium. The tinted dust which is thus produced is very effective in the representation of misty mountain effects, fogs, water spray and sea scenes.

Of course it is apparent that a certain amount of artistic ability and judgment is necessary in the practice of my new method of mural decoration. Its important advantage however, over the prior art practices, as by the use of stencils or the application of paint with a brush by the artist, resides in the fact that it is possible to greatly enhance the artistic effect of the decoration as a whole and to represent scenes and conditions which it is quite impossible to obtain by the usual methods of mural decoration.

I have above described the preferable procedure which I have actually used and found to produce very satisfactory results. Nevertheless, the detail steps of this method might be departed from in certain particulars, without materially effecting the ultimate result, and it is therefore, to be understood that my invention is not to be limited to the precise and exact procedure for the application of the different selected color media, as above explained, and that I reserve the privilege of resorting to all such legitimate changes therein as may be fairly considered within the spirit and scope of the invention as claimed.

I claim:

1. The method of decoration which consists in superimposing a plurality of different color media upon a plaster base and

producing a preconceived artistic effect by selectively removing different parts of the superimposed mediums to render the underlying color media visible, and then applying appropriate color media to the exposed portions of said superimposed media to modify the colors of the latter.

2. The method of decoration which consists in superimposing a plurality of different color media upon a plaster base and producing a preconceived artistic effect by selectively removing different parts of the superimposed mediums to render the underlying color media visible, and then applying appropriate color media to the exposed portions of said superimposed media to modify the colors of the latter, and finally applying a transparent fixative material.

3. The method of decoration consisting in successively applying unlike color media on a plaster base with an unlike color medium constituting a binder between the successively applied coats of the first color medium, then removing portions of the superimposed color media to render the underlying color media and the surface of the plaster base visible in accordance with a predetermined artistic conception, then applying other color media to the exposed parts of said superimposed coats of color medium and to the exposed plaster surface to modify the colors thereof, and finally applying a transparent fixative material.

4. The method of mural decoration, which consists in applying successive coats of selected color media over the entire surface of a plaster wall, permitting each coat to dry and interposing an unlike color medium constituting a binder between adjacent coats of the first color media, then subjecting the applied coats of the various color media at different portions of the wall surface to an abrasive action to expose any one of the underlying color media or the wall surface in accordance with a preconceived artistic design, then applying other color media to the exposed portions of said superimposed coats of color medium or the wall surface where required to modify the colors thereof, and finally applying a transparent fixative material upon the developed decoration.

In testimony that I claim the foregoing as my invention, I have signed my name hereto.

ROBERT M. SUTPHEN.
